UNITED STATES PATENT OFFICE.

FRIEDRICH BALTZER, OF BERLIN, GERMANY.

CAGE FOR ANTIFRICTION-BEARINGS.

1,114,332.

Specification of Letters Patent.

Patented Oct. 20, 1914.

Original application filed November 12, 1908, Serial No. 462,293. Divided and this application filed January 3, 1914. Serial No. 810,129.

To all whom it may concern:

Be it known that I, FRIEDRICH BALTZER, a subject of the Emperor of Germany, residing at Berlin, Germany, have invented certain new and useful Improvements in Cages for Antifriction-Bearings, of which the following is a specification, reference being had therein to the accompanying drawings, being a division of original application filed November 12, 1908, Serial No. 462,293.

This invention relates to antifriction bearings in which rolling elements are mounted between casing members, and has reference more particularly to the form and construction of the cage or spacing device usually employed to maintain the rolling elements in spaced relations, and embodying usually a ring or support equipped with holding members for the rolling elements.

The invention is directed to the production of a light and inexpensive cage in which the rolling elements will be held resiliently, and in which there will be provision for the ready detachment or removal of the holding members in the event of injury thereto; and the invention consists in a cage comprising a ring or support and a series of holding members carried thereby, said members consisting each of a strip of metal bent between its ends in the form of a loop to embrace the rolling element, and having its ends folded back on the sides of the loop and fastened to the support, preferably by interlocking said ends with the support to enable the members to be readily detached at will.

In the accompanying drawings I have shown my invention in the form and detailed construction which I prefer to adopt for the ends in view, but it will be manifest that the invention is susceptible of such modifications and changes as will suggest themselves to the skilled mechanic, and that the same is not limited to any particular form or construction of the parts except in so far as such limitations are specified in the claims.

Referring to the drawings: Figure 1 is a plan view of an antifriction bearing equipped with a spacing cage constructed in accordance with my invention. Fig. 2 is a sectional elevation through a portion of the cage, showing two of the holding members secured in operative position on the support, and one partially secured to show the method of removal and detachment.

In the accompanying drawings: My improved cage comprises a ring or support *a* adapted to fit between the inner and outer casing members 1 and 2 respectively of the bearing, and a series of holding members 3 for the rolling elements, which holding members are fastened to the support and formed each with opposing holder or clamping fingers 4 between which the rolling elements, in the present instance in the form of balls, 60 65 are embraced.

The holding members are formed each from a single piece or strip of thin metal, with its central portion bent in the form of a loop 5 to conform to the circumference of the ball, and its ends folded back on the sides of the loop to form shanks or tongues *c* for attachment to the supporting ring, which tongues are passed through slots in the ring and have their extremities 70 75 bent inwardly toward each other against the opposite face of the ring. These loops at the point where the folds are formed, are bent inwardly toward each other to conform to the circumference of the ball, 80 nearly meeting at this point, with the result that the loop practically surrounds the entire surface of the ball, which is thus held firmly but resiliently with spring pressure between the opposing sides of the loop. 85 From this construction it will be observed that each holding member retains its ball independently of the other, so that by setting the several members close together around the ring, as shown, the balls may be 90 arranged very close together and nearly the full complement used.

Furthermore it will be observed that by reason of the manner of fastening the members to the supporting ring, they may be 95 readily and individually detached without the necessity of employing special tools, it being only necessary to bend the confining tongues outward to the position shown at the bottom of Fig. 2, which will allow the 100 member to be drawn from the ring. This is of advantage and importance in the event of its being desirable to replace a worn holding member, and by reason of the fact that each member holds its balls independently 105 of the others, the removal of one will release but the one ball, the other balls being undisturbed.

The holding members are formed of a deformable material, that is, a material adapt- 110

ed to be bent to change its form, so that the members may be so interlocked with the ring as in the manner shown, that their independent removal may be effected at will 5 and without the use of special tools such as would be required if the holding members were riveted to the ring.

In setting up or assembling the parts of the bearing, the cage and balls are assembled in the casing members with the holding members in an unfinished form as represented at the bottom of Fig. 2, whereupon the unbent portions of the holding members are by suitable means, bent down on the 15 balls so as to embrace and retain them yieldingly in place, this action being permitted by the character of the material used in the formation of the members, which when bent down as described to embrace the balls, will 20 hold them resiliently and with a spring pressure.

While the invention is shown applied to a radial bearing, it may be employed also in connection with thrust bearings without material change in operation or function.

Having thus described my invention, what I claim and desire to secure by Letters Patent of the United States is as follows:

1. A spacing cage for antifriction bearings, comprising a ring or support and holding members for the rolling elements carried thereby, said members consisting each

of a metal strip bent between its ends in the form of a loop to embrace the rolling element, and having its ends folded back on 35 the sides of the loop and fastened to the support.

2. A spacing cage for antifriction bearings, comprising a ring or support, and holding members for the rolling elements 40 carried thereby, said members consisting each of a single strip of metal having its central portion bent in the form of a loop to embrace the rolling element, and having its ends folded back on the sides of the loop 45 and detachably interlocked with the support.

3. A spacing cage for antifriction bearings, comprising a ring or support provided at intervals with slots, and holding members 50 for the rolling elements carried by the support, said members consisting each of a strip of metal bent between its ends in the form of a loop to embrace the rolling element, and having its ends folded back on the sides 55 of the loop and passed through the slots in the support, and bent against the face of the same.

In testimony whereof I have affixed my signature in presence of two witnesses.

FRIEDRICH BALTZER.

Witnesses:

HENRY HASPER,
WOLDEMAR HAUPT.
